[57] CLAIM

The ornamental design for a frozen confection stick, as shown and described.

DESCRIPTION

FIG. 1 is a front elevational view of the frozen confection stick of the present invention, the rear elevational view being a mirror image thereof;

FIG. 2 is a front elevational view of an alternate embodiment of the frozen confection stick of FIG. 1, the only difference being the addition of an identical stick;

FIG. 3 is a left side elevational view of the frozen confection stick of FIG. 1;

FIG. 4 is a right side elevational view of the frozen confection stick of FIG. 1;

FIG. 5 is a top plan view of the frozen confection stick of FIG. 1; and,

FIG. 6 is a bottom plan view of the frozen confection stick of FIG. 1.

The broken lines showing of frozen confectionery in FIGS. 1 and 2 are for illustrative purposes only and from no part of the claimed design.
